UNITED STATES PATENT OFFICE.

ALBERT BLAUVELT, OF CHICAGO, ILLINOIS.

AUTOMATIC FIRE-EXTINGUISHER VALVE.

984,885.

Specification of Letters Patent. Patented Feb. 21, 1911.

Application filed March 8, 1909. Serial No. 482,083.

To all whom it may concern:

Be it known that I, ALBERT BLAUVELT, a citizen of the United States, residing at Chicago, in the county of Cook and State of Illinois, have invented certain new and useful Improvements in Automatic Fire-Extinguisher Valves, of which the following is a specification.

My invention relates to automatic fire sprinkler systems of the dry pipe type and the object thereof is to provide automatic valve mechanism for such systems which is of novel construction and efficient in operation, the same embodying features of advantage which will be made apparent from the description hereinafter given.

My invention relates more particularly to the mechanism or devices for controlling the action of the valves proper and the main object thereof is to provide for the positive opening of the valves when the pressure in the distributing pipes of the system has been reduced to the predetermined minimum for the operation of the system and the consequent applying of water thereto. Speaking in general terms, such controlling devices consist of novel and improved lever mechanism interposed between the water and air valves usual in dry pipe valves, which lever mechanism is by preference adapted to coöperate with a weight preferably arranged within the valve casing itself and in the same chamber with the lever mechanism, the construction and arrangement of such trigger mechanism and weight mechanism being such as to permit the said mechanism to operate irrespective of the weight which, however, is preferably employed to assure a more positive action of the valves and to cause them to be released more uniformly at a desired and predetermined reduction of pressure in the distributing system.

My invention also includes the provision of a cover plate for the valve casing, which cover plate is so constructed and adapted to coöperate with the valve mechanism as to insure the setting of the weight in operative position ready for action when the cover plate is applied and closed.

In the drawings Figure 1 is a central sectional elevation of my automatic valve showing the valves proper in closed position and the mechanism set ready for action; Fig. 2 a similar view but showing the valves and mechanism in operative position; Fig. 3 a

section on the line 3—3 of Fig. 1; Fig. 4 a section on the irregular line 4—4 of Fig. 1; and Figs. 5, 6 and 7 perspective views of the three members of the lever mechanism.

Referring to the present embodiment of my invention as illustrated in the drawings, the valve device or mechanism comprises a casing 1 having at its lower end an inlet opening 2 communicating with the usual riser 3 connected to a source of water supply and provided at its upper end with an outlet opening 4 communicating with the distributing pipes of the sprinkler system, the main pipe of which is illustrated at 5. In the present instance the valve casing is divided into two chambers 6 and 7, the former containing the so-called water valve and the trigger or lever mechanism between the valves and the latter the so-called air valve. The communication between the inlet opening 2 and chamber 6 is controlled by the water valve 8 normally seated upon its seat 9 and the communication between such chamber and the chamber 7 is controlled by the air valve 10 which is normally seated upon its seat 11. The trigger or lever mechanism hereinafter described in detail consists of a series of levers interposed between the two valves proper and preferably coöperating with a pivoted weight, it being understood that the air pressure of the sprinkler system acting downwardly upon the air valve 10 maintains the trigger or lever mechanism in its set position and the latter consequently holds the water valve upon its seat.

Describing the parts in detail, the water valve is mounted upon the lower end of an adjusting screw 12 which is screw-threaded through a bridge-piece 13 as shown in Fig. 1. This bridge-piece is pivoted at one end in the bearing lugs 14 extending upwardly from the bottom of the chamber 6, (Figs. 1, 2 and 5). The construction and arrangement of the bridge-piece and the valve casing are such that when the lever mechanism is released and the water valve opened by the pressure of the water supply, the valve and its bridge-piece will be swung wholly to one side of the water inlet in order to provide a free and unobstructed passage for the water as illustrated in Fig. 2. The water valve 8 may be mounted upon the adjusting screw in any suitable manner and as herein shown the lower end of such screw is provided with a head or flange 12^a fitting into a screw-

threaded recess or socket in the upper face of the water valve and held in position therein by means of the split nut 15.

The free end of the bridge-piece 13 is adapted to engage an intermediate trigger or lever 16 which, as clearly shown in the perspective, Fig. 5, is forked at its lower end by the provision of the parallel arms 16^a having similar irregular-shaped bearing 10 openings 16^b. One member of the fork is provided with a laterally-extending lug 16^c on which the weight is arranged to exert stress as hereinafter explained. The upper or free end of this intermediate lever terminates in a socket 16^d adapted to coöperate with the third member of the trigger mechanism as hereinafter explained. The members of the fork are connected on their inner sides by means of a cross bar 16^e whose lower 20 end is engaged by the free end of the bridge-piece 13. The intermediate lever is pivotally mounted upon a transverse bearing pin 17 which is cut away at its central portion where it passes through the intermediate lever, such pin being at this point half round, that is, semi-circular in cross section, as seen in Figs. 1 and 2. The ends of the bearing pin are left round and are adapted to bear in the bearing lugs 18 and 19 which here form a 30 part of the valve casing, the intermediate lever being arranged to oscillate in a plane between such bearing lugs as clearly shown in Figs. 3 and 4. The third member of the trigger mechanism, which is shown by itself 35 in the perspective, Fig. 7, consists of a strut 20 interposed between the upper end of the intermediate lever and the underside of the air valve, such strut being pivoted at 21 in the forked and depending head of a screw 40 22 which extends upwardly through the air valve and is held in place by means of the nut 23. This strut is pivoted at one side of its central point thereby providing a longer arm 20^a and a shorter arm 20^b, the longer 45 arm engaging the intermediate lever and the shorter arm being arranged to engage or contact the air valve, in the present instance such contact being against a curved or socket portion 24 of the head of the screw 22 at a 50 point at the base or inner ends of the members of the forks of such head, Figs. 1 and 3. In order that the upward pressure on the air valve exerted by the strut shall be such as to lift the valve upwardly in a horizontal plane 55 and prevent the same from being canted, I prefer to locate this contact 24 between the strut and the air valve on the same plane or substantially the same plane as the seat 11 of such air valve. By reason of the connecting of the strut with the air valve, such strut is held to the latter and removed from 60 interference with the flow of water by the opening of such air valve, as shown in Fig. 2. Furthermore, by reason of the pivoting 65 of such strut to the air valve and the pro-

tection of the longer and shorter arms, the restoring of the air valve to normal or closed position automatically brings the strut to its proper or normal position ready for the setting of the trigger mechanism, the longer 70 arm 20^a being the heavier and consequently swinging the strut to such normal position. It will be understood that the air valve is pivoted in its chamber 7, the same being pivoted upon the lever arm 25.

In practice the valves proper are seated and the three members of the trigger mechanism are set as shown in Fig. 1 and the adjusting or tension screw 12 is screwed downwardly in order to hold the water valve upon its seat and to supply some tension or stress upon the trigger mechanism, which stress is resisted by the pressure of the sprinkler system acting downwardly upon the air valve 10. When this air pressure is reduced to a predetermined amount through any cause such as the opening of a sprinkler head, the trigger mechanism is released, the strut 20 being permitted to oscillate and the intermediate lever and bridge-piece being thereupon permitted to swing in opposite directions and free of the water passage, as clearly shown in Fig. 2.

The parts as thus far described constitute a practical and operative structure but in practice it is found that the operators or engineers in setting the trigger mechanism apply widely different degrees of pressure to the trigger mechanism upon screwing down the adjusting screw 12, with the result that a valve or a set of valves will be operated at different degrees of reduction of pressure in the sprinkler system. To overcome this difficulty and to supplement the action of the trigger mechanism and to cause it to be actuated more positively and uniformly according to a certain degree of reduction of pressure, I employ a weight device coöperating with the trigger mechanism. As shown and by preference this weight device is in the same chamber 6 as the trigger mechanism, the case being somewhat swelled out on one side at 1^a, Fig. 3, in order to accommodate the weight. The weight device consists of a weight proper marked 26 which is pivoted upon a bearing pin 27 through the medium of a yoke 28, one of whose arms is extended at 29 for attachment to such weight, as clearly indicated in Fig. 4. This yoke is in the form of a bail whose cross arm 28^a is adapted to bear upon the lug 16^c of the intermediate lever. The weight 6 is of a predetermined weight and by reason of its described coöperation with the intermediate lever it is arranged to constantly exert, while in set position, a fixed and uniform amount of pressure or stress upon the trigger mechanism. As shown in Fig. 1 the cross bar 16^e of the intermediate lever is located close to and at one side of

the bearing pin 17 while the lug 16^c is located at the opposite side thereof, with the result that the lower edge of such cross bar serves as a fulcrum for the action of the 5 weight, the bearing pin 17 being cut away in the described manner in order that this result may be accomplished. The weight therefore maintains a constant stress tending to unseat the air valve 10, supplementary to the more or less fluctuating stress which is imparted by the varying pressure of the water as transmitted by the adjusting screw 12, so that differences in such pressure and the adjustment of the screw do not 10 cause a great variation in the total stress tending to lift the air valve. The result of the employment of the weight thus is that the needful degree of reduction of air pressure to release the valve mechanism is 15 kept within a rather narrow range, which is quite important in automatic sprinkler practice.

Another feature of my invention relates to a provision for compelling that after the 20 trigger mechanism is set the weight shall also be in set or operative position before the cover plate for access or working opening to the chamber 6 can be applied and secured in place. To this end the cover 25 plate 30, which in the present instance is pivoted to the casing 1 at 31 and secured in place by the fastening bolts 32 is provided on its inner face with an inwardly-extending lug 33, Figs. 3 and 4, adapted to 30 coöperate with a rod 34 which at its front or outer end is bent at a right angle to form a handle or lever 34^a which may be oscillated in a plane parallel with the cover plate 30 to rotate the rod. The rear end of the 35 rod is also bent, in a direction parallel with the front end, and lies below or within a recess formed in the bottom of the weight 26, Figs. 2 and 4. This rod 34 thus provides means whereby the operator or engineer may as a needed working convenience 40 elevate the weight so it will not interfere with manual resetting or restoring of the trigger mechanism to normal position. When the trigger mechanism proper is thus 45 restored the handle 34^a must of necessity be restored to normal position and lower the weight into normal working position in doing so, else the handle will interfere with closing of the cover plate 30 as is necessary 50 to complete the operative setting of the valve. Except for such provision the operator might forget to properly place the weight and close the valve without benefit of the weight.

55 In this art as practiced by others the fact that the cover plate must necessarily and to the mind of the operator unfailingly be closed as a completion of the setting of this type of valve has not heretofore been made 60 of avail to insure that the valve mechanism

in full be properly set before the cover plate is closed by designing said cover plate to be in positive mechanical coöperation with the valve mechanism.

My invention in its broader aspect is not 70 to be confined to the particular form of mechanical coöperation shown because other practical means may be adopted, the hand lever and cover plate lug herein shown being, however, very simple and efficient for 75 the purpose in view.

I claim:

1. The combination with the casing of an automatic sprinkler valve and valve mechanism therein comprising a train of 80 operating mechanism, a weight coöperating therewith, and a lever arranged to be shifted in one position to lift said weight and permit said operating mechanism to be set, and shifted in the other position to permit the 85 weight to assume coöperative relation with the operating mechanism, of a cover plate for said casing, said cover plate having an inwardly-projecting lug arranged to interfere with said lever when the latter is in 90 its first-mentioned position and thereby prevent the application of the cover plate to the casing, and not to interfere with such lever when it is in its last-mentioned position.

2. In an automatic sprinkler system, the combination with the casing and with the valves, air and water, and valve actuating mechanism therein, of an independent movable weight mounted to rock in bearings 100 seated in said casing and tending through connection with the operating mechanism to open said air valve, said weight being located within the casing.

3. In an automatic sprinkler system, the combination with the casing having an inlet communicating with a source of water supply and an outlet communicating with the distributing pipes of the system, a water valve governing said inlet, an air valve governing said outlet, and with trigger mechanism comprising a series of interengaging levers interposed between the valves and dependent for set position upon the pressure of the system on the air valve, of a weight 110 pivotally mounted independently in bearings in the walls of and arranged within the casing and adapted to exert its stress upon the levers, the latter being arranged to operate with or independently of the weight.

4. In an automatic sprinkler system, the combination with the casing having an inlet communicating with a source of water supply and an outlet communicating with the distributing pipes of the system, a water valve governing said inlet, an air valve governing said outlet, and with trigger mechanism interposed between the valves and comprising a bridge piece coöperating with the water valve, a strut coöperating with the 125 130

air valve, and an intermediate lever pivoted to rock in bearings within the casing acting as a trigger between the bridge piece and the strut, a screw for exerting pressure between 5 the water valve and bridge to provide some of the stress upon the trigger mechanism, of a weight mounted to rock within the casing independently of the trigger mechanism and adapted to coöperate with said intermediate 10 lever and to provide a constant amount of supplemental stress upon such mechanism.

5. In an automatic sprinkler system, the combination with the casing having an inlet communicating with a source of water supply and an outlet communicating with the distributing pipes of the system, a water valve governing said inlet, an air valve governing said outlet, and with trigger mechanism interposed between the valves and comprising a bridge piece coöperating with the water valve, a strut coöperating with the air valve, and an intermediate lever acting as a trigger between the bridge piece and the strut, a screw for exerting pressure between 20 25 the water valve and bridge piece to provide some of the stress upon the trigger mechanism, of a weight mounted to rock within the casing independently of the trigger mechanism and adapted to coöperate with said intermediate lever and to provide a predetermined amount of stress upon such mechanism, and a rocking lever within the casing for elevating said weight when the trigger mechanism is to be set.

35. 6. In an automatic sprinkler system, the combination with the casing having an inlet communicating with a source of water supply and an outlet communicating with the distributing pipes of the system, a water valve governing said inlet, an air valve governing said outlet, and with trigger mechanism interposed between the valves and comprising a bridge piece coöperating with the water valve, a strut coöperating with the air 40 45 valve, and an intermediate lever acting as a trigger between the bridge piece and the strut, means for exerting stress between the water valve and bridge piece, of a pin on which said intermediate lever oscillates and 50 which has a cut-away portion where it passes through such lever to permit the latter moving in a direction transverse to said pin when the trigger is tripped, and a weight adapted to coöperate with said intermediate 55 lever by exerting stress thereupon.

7. In an automatic sprinkler system, the combination with the casing having an inlet communicating with a source of water supply and an outlet communicating with the distributing pipes of the system, a water valve governing said inlet, an air valve governing said outlet, of trigger mechanism interposed between the valves and comprising a bridge piece coöperating with the water 60 65 valve, a strut coöperating with the air valve,

and an intermediate lever acting as a trigger between the bridge piece and the strut and having a pivot opening and a cross-bar adjacent said opening which cross-bar is engaged by the bridge-piece, a pivot pin for 70 said intermediate lever, which pin is cut away on one side where it passes through such lever, and a weight adapted to coöperate with said intermediate lever by exerting stress thereupon. 75

8. In an automatic sprinkler system, the combination with the casing having an inlet communicating with a source of water supply and an outlet communicating with the distributing pipes of the system, and with the water valve governing said inlet and the air valve governing said outlet, of trigger mechanism interposed between the valves and comprising a bridge piece coöperating with the water valve, a strut coöperating 80 85 with the air valve, and an intermediate lever acting as a trigger between the bridge piece and the strut and having a pivot opening, a cross-bar adjacent said opening and at one side thereof and a projecting lug at the opposite side of such opening, a pivot pin in said opening, and a weight adapted to coöperate with said intermediate lever by exerting its stress upon said lug, said bridge piece engaging the cross-bar. 90 95

9. In an automatic sprinkler system, the combination with the casing having an inlet communicating with a source of water supply and an outlet communicating with the distributing pipes of the system, and with the water valve governing said inlet and the air valve governing said outlet, of trigger mechanism interposed between the valves and comprising a bridge piece coöperating 100 105 with the water valve, a strut coöperating with the air valve, and an intermediate lever acting as a trigger between the bridge piece and the strut, and having a pivot opening, a cross-bar adjacent said opening and at one side thereof and a projecting lug at the opposite side of such opening, a pivot pin in said opening, and a pivoted weight having a yoke adapted to bear upon said lug and to thereby exert stress upon the trigger mechanism. 110 115

10. In an automatic sprinkler system, the combination with the casing having an opening in one side an inlet communicating with a source of water supply and an outlet communicating with the distributing pipes of the system, a cover plate for said opening and with the water valve governing said inlet and the air valve governing said outlet, of trigger mechanism interposed between the valves and comprising a bridge piece coöperating with the water valve, a strut coöperating with the air valve, and an intermediate lever acting as a trigger between the bridge piece and the strut, a pivoted weight adapted to exert stress upon a portion of the 120 125 130

intermediate lever, and a rocking lever adapted to be manually operated to elevate said weight to permit the trigger mechanism being set and afterward to lower said weight onto said trigger mechanism, the latter movement of the lever being necessary to permit restoration of the cover plate.

11. In an automatic sprinkler system, the combination with the casing having an inlet communicating with a source of water supply and an outlet communicating with the distributing pipes of the system, and with the water valve governing said inlet and the air valve governing said outlet, of trigger

mechanism interposed between the valves 15 and comprising a bridge piece coöperating with the water valve, a strut coöperating with the air valve, and an intermediate lever acting as a trigger between the bridge piece and the strut, and a forked lower end with a 20 connecting cross bar engaged by the bridge piece, one of the members of the fork having a projecting lug, and a weight adapted to exert stress upon such lug.
